STRINGED MUSICAL INSTRUMENT

Clair Omar Musser, 12997 Blairwood Drive,
Studio City, Calif. 91604

Filed Feb. 8, 1967, Ser. No. 5,724

Term of patent 14 years

(Cl. D56—1)

FIG. 1 is a top plan view of a stringed musical instrument showing my new design thereof;

FIG. 2 is a bottom plan view thereof;

FIG. 3 is a front elevational view thereof;

FIG. 4 is a left end elevational view thereof; and

FIG. 5 is a right end elevational view thereof.

The rear elevational view is symmetrically identical to FIG. 3.

I claim:

The ornamental design for a stringed musical instrument, substantially as shown and described.
